UNITED STATES PATENT OFFICE.

CHARLES A. BAILEY, OF COBALT, CONNECTICUT, ASSIGNOR OF ONE-HALF
TO ALONZO B. BAILEY AND HARRISON BRAINARD.

DESIGN FOR A COFFIN-HANDLE EAR.

SPECIFICATION forming part of Design No. 12,164, dated February 15, 1881.

Application filed January 8, 1881. Term of patent 3½ years.

To all whom it may concern:

Be it known that I, CHARLES A. BAILEY, of Cobalt, in the county of Middlesex and State of Connecticut, have originated and invented a new and useful Design in Coffin-Handle Ears; and I do hereby declare that the following is a full, clear, and exact description thereof, reference being had to the accompanying drawings, forming a part of this specification, in which—

Figure 1 is a plan view. Fig. 2 is a side view.

This invention relates to designs for the ornamentation of ears for the attachment of handles to coffins.

The invention consists in the details hereinafter described.

The leading feature of my design consists in a diamond-shaped projection in the center, 20 grooves running at right angles across the face of the ear, and angular projections formed by said grooves along the edges of said face.

In the drawings, A is a diamond-shaped projection at the center, having projecting 25 lugs a a, for the attachment of the handle, and an opening in the top to receive the attaching-lug of said handle. Running across the ear lengthwise are two parallel grooves, and at right angles to these, transverse the 30 ear, two other parallel grooves, the latter being farther apart than the former. These grooves form an inner parallelogram, on which diamond A is seated, the points a' of said diamond crossing the bottoms of said grooves 35 and striking the projections beyond. The outer edges, d d', of the ear are beveled off, as shown. The grooves and the beveled edges d and d' form the angular projections E, E', F, F', and G. The projections G are pyramidal in shape and the same size. The projections E E' and F F', occupying the places 40 between the ends of the grooves, are elongated, and have beveled ends and sides.

The diamond A is curved downward at n, 45 and has its top portion, o, above the bottom portion, n, and flat. The surfaces of these two portions have spaced diagonal ribs run-

ning across, with intervening rows of circles or dots, the ribs upon portion o running in both directions at right angles.

The edges m of the diamond are beveled off, as shown.

The corner pyramids, G, have upon the top a circle within a square, and extending from said top, down each side, a loop, each of said 55 sides outside the loop having grooves channeled across their faces horizontally.

The projections F F' have upon their outer edges, at the middle, two trefoils, p p, having their ends meeting within the face of the 60 edge, and projecting outwardly along the face of said edge from these meeting ends are sprays of cedar. Curved lines or ribs run from the corners of this face to said sprays. The remainder of said face is covered with 65 the heraldic dots for ermine. The inner faces have running lengthwise alternate grooves and ribs, formed in dots. The ends have rows of circles, with crossed diameters indicated, the circles being in line horizontally and out 70 vertically. The tops are composed of squares, the alternate ones having dots in them.

The tops of projections E E' have a similar 75 design. The outer edge of projection E is like wicker-work arranged straight, the inner edge, smaller wicker-work arranged diagonally. The ends have the ermine dots. The inner edge of projection E' is similar to that of projection E. The ends of this projection 80 E' are similar to those of projections F F'. Along the lower edge of the outside of projection E' is the tie q, whose point r is outward, and its scroll ends s s turned inward. Along the top of this outer edge is an M, 85 whose scroll ends t t meet scroll ends s s nearly. Between this M and the tie are arranged the two kinds of wicker-work already referred to.

Around the lower parts of the edges of the 90 pyramids G may be arranged the bottom of the drapery of a pall.

What I claim is—

1. A design for ears for coffin-handles, here-

(over)

in shown and described, consisting of the diamond-shaped central projection, the grooves, and the outer angular projections.

2. The design for ears for coffin-handles, 5 herein shown and described, consisting of the central diamond-shaped projection, the grooves running at right angles and parallel in pairs, the pyramidal corner, and intermediate elongated projections.

In testimony that I claim the foregoing as to my own I affix my signature in presence of two witnesses.

CHAS. A. BAILEY.
